UNITED STATES PATENT OFFICE.

ROY WADE, OF POCATELLO, IDAHO.

HEATING APPARATUS.

1,410,431.

Specification of Letters Patent. Patented Mar. 21, 1922.

Application filed June 15, 1920. Serial No. 389,106.

To all whom it may concern:

Be it known that I, ROY WADE, a citizen of the United States, residing at Pocatello, in the county of Bannock and State of Idaho, have invented new and useful Improvements in Heating Apparatus, of which the following is a specification.

This invention relates to an improved heating apparatus for heating dwellings and the like and the principal object of the invention is to provide means for causing a circulation of the air in the dwelling with means for imparting heat to the air at one point in its circulation by a body of heated water, the water being available for other use when desired.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a sectional view showing a portion of a dwelling with my invention in use.

Figure 2 is a section on line 2—2 of Figure 1.

Figure 3 is an enlarged view of the means for applying moisture to the air.

Figure 4 is a section on line 4—4 of Figure 3.

Figure 5 is a diagram of the electric circuit.

In these drawings 1 indicates the basement of a dwelling and 2 one of the rooms above. A casing 3 is located in the basement and this casing is preferably of tapered formation, as shown in the drawing. The small end of said casing is connected by a pipe 4 with a register 5 located in the room 2 and an electric fan 6 is arranged in the small end of the casing so as to cause the air from room 2 to pass down the pipe 4 into the casing. The large end of the casing is fitted

50 with a radiator 7 which is somewhat similar to an automobile radiator. The air leaving this radiator will pass into a chamber 8 and from this chamber it flows to the room, or rooms, through the pipes 9, which lead to

the registers 10. A water tank 11 is placed 55 in the basement and the lower part of said tank is connected with an electric water heater 12 and this heater is connected with the bottom of the radiator by the pipe 13. The top of the tank is connected with the 60 radiator by pipe 14 which connects with the top of the radiator. Tank 11 is connected with a suitable source of supply by pipe 15 and water may be drawn from said tank by pipe 16. As shown in the diagrammatic 65 view the electric heater coil is connected with the main source of supply by the conductors 17, in which is located the switch 18 and the electric fan is connected with said main by the conductors 19 in which is located the 70 controlling switch 20. This switch 20 is of a type to give the fan various speeds.

In order to moisten the air passing through the device I locate strips 21 of felt or the like in front of the radiator, the upper 75 ends of the strips passing into a slotted pipe 22. The ends of this pipe are closed and water is supplied to said pipe by means of a small pipe 23 which is connected with pipe 14. This pipe 23 has a regulating valve 24 80 therein. The water in the slotted pipe will saturate the strips of felt and thus add moisture to the air passing from the radiator and at the same time collect any dust 85 which is in the air.

It will thus be seen that a circulation of the air within the dwelling will be set up when the fan is operating and this air passing through the radiator will be heated by the hot water circulating through the pipes 90 of the radiator. This hot water is available for use in the dwelling and thus it serves a double function.

In hot weather cold water may be caused to circulate through the radiator so as to 95 cool the air passing through the casing. It will of course be understood that the water may be heated by gas or the like though I prefer to use electricity.

My invention insures a clean, inexpensive 100 and even heat for the heating of buildings and is more particularly adapted to small dwelling houses.

It is thought from the foregoing description that the advantages and novel features of my invention will be readily apparent.

I desire it to be understood that I may make changes in the construction and in the

combination and arrangement of the several parts, provided that such changes fall within the scope of the appended claims.

I claim as my invention:—

- 5 1. An apparatus of the class described comprising a casing, means for connecting the same with a room to be heated, a fan in said casing for causing the air to circulate, a radiator at one end of the casing, a water
- 10 10 tank connected with said radiator, means for heating the water for causing the water to heat the air passing through said radiator and means for drawing water from said tank.
- 15 2. An apparatus of the class described

comprising a casing, means for connecting the same with a room, a fan in said casing causing the air to circulate, a radiator at one end of the casing, means for passing water through said radiator and an air 20 moistener and cleaner located in front of said radiator, said device comprising a slotted container carried by the radiator, valved means for supplying the same with water from said radiator and strips of absorbent 25 material having their ends engaged in said slot and said strips extending in front of the radiator.

In testimony whereof I affix my signature.

ROY WADE.
